United States Patent Office.

JOSEPH W. JUNE, OF WHEELING, WEST VIRGINIA.

Design No. 3,874, dated March 1, 1870.

DESIGN FOR AN INKSTAND.

The Schedule referred to in these Letters Patent and making part of the same.

I, JOSEPH W. JUNE, of Wheeling, in the county of Ohio, and State of West Virginia, have invented and produced a new and original Design for an Inkstand, and do hereby describe the same.

The accompanying photographic illustration is a front view of an inkstand having my design.

The design consists in the association in and on a base or stand, A, and a pair of standards, B B, erected thereon, of a bottle, C, for the reception of the ink, a drawer, D, for paper, &c.; a pair of urns, C C, for nibs, wafers, &c., and pen-racks D D, which may be pre-

sented either sidewise or forward, substantially as represented.

Claim.

I claim the design for an inkstand, substantially as represented and described.

In testimony of which invention I hereunto set my hand.

JOSEPH W. JUNE.
